CLAIM

The ornamental design for a chair, substantially as shown and described.

DESCRIPTION

FIG. 1 is a perspective view of a first embodiment of my new design;

FIG. 2 is a side elevational view of the embodiment of FIG. 1, the opposite side view being a mirror image thereof;

FIG. 3 is a front elevational view of the embodiment of FIG. 1;

FIG. 4 is a rear elevational view of the embodiment of FIG. 1;

FIG. 5 is a top view of the embodiment of FIG. 1;

FIG. 6 is a perspective view of a second embodiment of my new design, the front rear and top views being identical to those for the embodiment of FIG. 1; and,

FIG. 7 is a side elevational view of the embodiment of FIG. 6, the opposite side view being a mirror image thereof.

The fragmented pattern shown on the seat and backrest is understood to represent fabric and would be continuous throughout the circumscribed areas.
